UNITED STATES PATENT OFFICE

2,561,907

WINDOW

Francis J. Claveloux, Washington, D. C.

Application June 1, 1948, Serial No. 30,316

5 Claims. (Cl. 268—104)

1

This invention relates to windows. More particularly, it relates to a window having a sash of a swinging as distinguished from the more usual sliding type, the sash being so mounted that it can selectively be pivoted on a horizontal axis, on a vertical axis, or removed entirely from its frame.

By way of background, it may be pointed out that windows that pivot outwardly on horizontal axes, sometimes called awning type windows, have certain recognized advantages over the double hung window. For example, when open they give maximum ventilation while yet constituting a shield against rain, wind, and the elements in general. For these and other reasons, they have been gaining in favor not only in warm and rainy sections of the country, where they have probably their most widespread use, but in other sections as well.

Windows mounted to give access both to their interior and exterior pane surfaces, from inside the house, are also desirable for the reason that they can be cleaned speedily and without danger. To this end, removable sashes have already been devised. However, the disadvantages are noted in connection with removable sashes, that they tend to fit rather loosely when closed, thus to admit outside air to an undesired extent. Additionally, they must be removed entirely to permit cleaning of both their interior and exterior pane surfaces, and thus must either be supported upright by the housewife while being cleaned, or else must be laid upon the floor or against the wall or furniture, to the inconvenience of the housewife and possible soiling of the supporting surface.

In the window which I have devised, it is possible to remove the sash entirely if desired, thereby to permit ready repair of a broken pane, or carrying to a central point for cleaning or maintenance purposes. However, the sash can, rather than be removed entirely, swing on a vertical axis, so as to be fully supported in its frame while yet permitting access to its exterior and interior surfaces while cleaning.

The primary purpose of the invention has been to provide a window having all these advantages. Other purposes are to provide a window which will have these several features, and which will yet be relatively inexpensive of manufacture; which will be durable; easily operated; and readily fabricated from such materials as aluminum or the like.

With the foregoing and other objects in view which will appear as the description proceeds, the invention consists of certain novel details of con-

2

struction and combinations of parts, hereinafter more fully described and pointed out in the claims, it being understood that changes may be made in the construction and arrangement of parts without departing from the spirit of the invention as claimed.

Referring to the drawings:

Figure 1 is an elevation of a window constructed in accordance with the invention, as seen from inside a room.

Figure 2 is an enlarged section on line 2—2 of Fig. 1 showing an air aperture formed in the movable sash when the window is made of double paned construction.

15 Figure 3 is a fragmentary perspective view showing one upper corner portion of the sash.

Figure 4 is a perspective view of a movable spacer member.

Figure 5 is a section taken substantially on line 20 5—5 of Fig. 1.

Figure 6 is a perspective view of a rack and pinion means used in positioning the sash for swinging on a vertical axis.

Figure 7 is a fragmentary plan view of the 25 crank illustrated in Fig. 6.

Figure 8 is a perspective view of a retractable pivot pin carried by the movable sash, on which it pivots for swinging on a horizontal axis, a portion of the sash being shown in dotted lines.

30 Figure 9 is a view, partly in elevation and partly in vertical section, of a portion of the window frame and the window operating mechanism carried thereby.

Figure 10 is a section on line 10—10 of Fig. 9.

35 Figure 11 is a view of the operating mechanism taken on the left of Fig. 9, portions of the window frame being removed.

Figure 12 is a perspective view of the upper portion of a side jamb.

40 Figure 13 is a perspective view of the upper portion of the other side jamb.

Referring to the drawings in detail 14 generally designates a window frame. This is of generally conventional design, having a sill 15, side casings 16 and 17, and top casing 18. The window of the invention, in fact, can be mounted in a conventional frame which may already be in a house, or alternatively can be manufactured with its own frame, as would be desired when the window is being installed in a house during erection of the house itself.

The frame is equipped with a window stool 19 to provide a stop for the swinging sash, and a support for a window screen, both of which will be described hereinafter.

3

Mounted to the inner surfaces of the side casings 16 and 17 respectively are side jambs 20 and 21. A header 22 is fixedly secured at its ends to the tops of the respective side jambs, so as to extend transversely of the window. The reference character 23 designates a fixed upper sash 23. This could be omitted entirely, if the swinging lower sash illustrated is made of a size to fill the entire window frame opening.

With the exception of the fixed upper sash 23, all the parts so far described constitute a fixed supporting frame for the window.

Referring to Figs. 1, 4, and 5, a spacer member 24 is generally L-shaped in cross section, having a depending flange 25 that constitutes the upper stop for a window screen 26 that is supported at its lower end by the window stool 19. The screen 26 is simply pressed into position, from inside the room, and can readily be gripped by the window frame by being equipped with suitable springs along its sides. These are a common expedient, and accordingly it has not been felt necessary to illustrate them specifically.

Extending from the ends of the spacer 24 are lugs 27 respectively loosely received in L-shaped guide ways 28 and 29 (Figs. 12 and 13), carried at the upper ends of the side jambs 20 and 21.

Normally, the spacer 24 is positioned as in Fig. 5, and when so positioned, underlies the header 22. The spacer when so positioned is supported to the header by U-shaped hooks 30 carried by the spacer, the free ends of which extend into openings 31 of the header.

This is the position of the spacer when a movable sash generally designated 32 is being used as an awning type window, as when swung to the dotted line position of Fig. 5. For a reason which will later be apparent, however, the spacer 24 is on occasion swung out of this position. To swing the spacer out of its normal position, and position it inoperatively, one need only remove the screen 26, and pull the spacer to the right in Fig. 5. This disengages hooks 30 from openings 31, whereupon the spacer can be drawn to the right in Fig. 5 to the full extent of travel of the lug 27 in the horizontal portions of the guide-ways 28 and 29. Then, the spacer is elevated, the lugs now moving in the vertical portions of the guide ways, and swung over upon the upper surface of header 22.

The movable sash 32 can be of single or double paned construction as desired. In the present instance, and preferably, it is double paned as shown at 33. When this double glass design is used, the side rails 35 of the movable sash are formed with air apertures 36 (Fig. 2), so that air can be cleaned and dried before being entered during the manufacture of the sash, the apertures 36 then being closed by plugs 37.

The upper rail of the movable sash is designated 38 and at its opposite ends (see Fig. 8) has mounted therein pin housings 39, in which are slidably mounted pins 40 that project beyond the sides of the movable sash 32, the projecting ends of the pins being provided with enlarged heads 41. Normally, the pins are pressed outwardly from the sides of the sash by springs 42. However, they can be retracted simultaneously through the provision of rods 43 fixedly connected to the pins 40, that slide in brackets 44 and are formed at their free ends with finger grips 45. As seen from Fig. 1, the grips 45 are spaced apart a distance permitting one to press them toward each other with ease, whereupon both the pins 40 are simultaneously retracted.

When the movable sash 32 is in the full line closed position of Fig. 5, the transversely rounded surface of the upper rail 32 thereof is tightly engaged by a curved metallic strip 46 of springable material, that constitutes a weatherstrip. The sash itself, as may be noted from Fig. 3, may be and preferably is also weatherstripped along its respective frame engaging edges.

In normal use for ventilating purposes, sash 10. 32 is used as an awning type window, swinging in the direction of the arrow of Fig. 5, and when so used, it pivots on and is supported by the pins 40 equipped with heads 41, and will thus be seen that the window sash 32 thus swings on 15 a horizontal axis when so used, said axis being located near the upper end of the sash.

During such use, the heads 41 extend into openings 47 and 48 in the side jambs 20 and 21 respectively. These are best seen in Figs. 12 and 20 13.

Openings 47 and 48 are in communication with L-shaped slots 49 and 50 respectively. When the heads 41 are simultaneously retracted, they withdraw into these slots. One of these slots opens to the room, while the other opens to the outside, and it will therefore be seen that if after retracting the heads 41 so that they are no longer engaged in the openings 47 and 48, but rather are in the slots 49 and 50, the sash is elevated in its entirety a short distance, the sash can then be swung on a vertical axis, with the heads 41 clearing through the horizontal portions of the slots so as to permit free rotation of the sash. The means for so elevating the sash, and rotating it on a vertical axis, will be described hereinafter.

I provide a means for swinging the window sash in and out during normal use, this being best shown in Figs. 9 and 11. A supporting bracket 51 is of U-shaped formation, and is secured fixedly to the side casing 17, in the hollow interior portion thereof. This bracket supports a gear box 52 having upwardly extended ears 53. A bowed spring 54 has secured to its ends pivot pins 55. The ears 53 and the arms of the brackets 51 have receiving openings that are adapted to be brought into register. Thus, by compressing the spring 54 during assembly of the device, the pins 55 can be positioned to be entered into the registering openings. Thereupon, the spring is released, and the gear box 52 is thus pivotally suspended from the bracket.

Journalized in the side walls of the swinging gear box is a shaft 56 and mounted for rotation with the shaft is a worm 51. The shaft extends through the side of the casing 11, and is equipped with an operating crank 58. The casing 11 has an opening 59 of suitable size to permit projection of shaft 56 therethrough, and also another shaft to be described. The opening is covered by a cover plate 60 secured by suitable fastening means to the casing 11.

The worm 57 meshes with a pinion 61, rotatable with shaft 62 having at its inner end the driven crank 63. Referring now to Fig. 3, the adjacent side of the sash is recessed and mounted in the recess is a cup 64 having a longitudinal slot 65 opening into an enlarged opening 66. As will be observed from Fig. 9, the crank 63 is equipped with a button, and this is adapted to enter into the opening 66 and then into the slot 65.

When the button is engaged in the slot, operation of the crank 58 results in the window being swung as in Fig. 5, and it will be understood that

the sash can be either open or closed, depending on the direction of rotation given the crank 58.

In this connection, the driven crank 63 can be positioned in operative and inoperative positions respectively, these being illustrated in Fig. 9. When positioned inoperatively, as shown by dotted lines in this figure, it recesses in a cut-away portion 67 formed in the inner surface of the side jamb 21 (Figs. 9 and 12), the shaft 62 to which the crank is mounted being vertically movable in a slot 68 communicating with the cut-away portion, for swinging of the driven crank into its operative and inoperative positions.

As a means for swinging the driven crank into these positions, a locking rod 69 is provided, that projects from the side of the casing 17 for ready access by a user. The locking rod 69 carries a rod 70, pivotally received in an opening formed in the side wall of the gear box 52. The lock rod 69 has a pair of spaced slots 71, either of which are adapted to be engaged with a stud 72 carried by the cover plate 60. Thus, when the lock rod 69 is retracted to the dotted line position illustrated in Fig. 9, and one of the slots 71 engaged with the stud, the gear box, and hence the driven crank 63, will be positioned inoperatively. However, when it is desired to swing the driven crank into operative engagement with the sash 32, the rod 69 is elevated from the stud 72, pressed inwardly, and its other slot 71 is placed in engagement with the stud. This has the result of pivoting the gear box to the left in Fig. 9. When the gear box has been so moved, the driven crank 63 is in operative engagement with the sash 32, and rotation of the crank 58 will cause the sash 32 to be swung outwardly.

The purpose of providing a retractable driven crank 63 is to permit its retraction when it is desired to swing the sash 32 on a vertical axis. As to swinging the sash on its vertical axis, reference should be had to Figs. 5, 6, and 7, which best illustrate this operation. A rack 73 is vertically mounted for sliding movement in the bottom rail of the sash 32, and can be entered into or withdrawn from socket 74 provided in the sill.

15. For the purpose of reciprocating the rack 73, a pinion 75 in mesh with the rack and mounted in the lower rail of the sash is carried by a shaft 76 rotatable by an operating crank 77. Crank 77 is equipped with a spring pressed 50 detent 78. Normally, the detent is pressed toward the lower rail of the sash, and thus can be entered into and retained in one or more openings 79 provided in the lower rail. To withdraw the detent from the opening 79, the user simply exerts pull upon the handle of the crank, the detent being secured fixedly to said handle as best shown in Fig. 7.

In axial alignment with the rack 73 is a vertical pivot pin 80 at the upper end of the sash, this being mounted in the header 22, and having one end projecting below the header. It may now be noted that in Fig. 5, the rack 73 is positioned inoperatively, that is, it is fully retracted within the lower rail of the sash so as to permit normal swinging use of the sash. In this connection, on initial downward movement given the rack 73, the rack will enter into the socket 74, and serves as a lock whereby the window is held in locked position when not in use.

Not only is the rack 73 capable for use as a lock for the window however. If continued rotation is given the crank 77, the rack 73, after it has engaged the bottom of the socket 74, will 75

cause the entire sash 32 to be elevated. When elevated, the upper vertical pivot pin 80 will be entered into an opening 81 provided in the upper end of the sash 32, and thus the sash 32 is supported for rotation on a vertical axis. The line of the vertical axis is the same as section line 5-5 of Fig. 1.

The spacer member 24 has a slot 82 opening from its outer longitudinal side (Figs. 4 and 5), so that the spacer can be placed in the position illustrated in Fig. 5, with the slot 82 permitting passage of that portion of the spacer which would otherwise be halted by the downwardly extended vertical pivot 80.

15. In use, the sash 32 is used as an awning type window. During such normal use, spacer 24 is mounted as shown in Fig. 5, and constitutes a stop for the screen 26 and also a means for weatherstripping the upper edge of the sash 32. Gear box 52 is swung to the dotted line position illustrated to the left in Fig. 9 and locked in said position. Rack 73 is fully withdrawn into the lower rail as shown in Fig. 5.

The sash can now be swung outwardly and inwardly, and has full use as an awning type window. It can be locked in closed position simply by dropping the rack 73 sufficiently to engage it in the socket 74.

Assuming that it is desired to clean the exterior and interior surfaces of the sash, gear box 52 is first withdrawn to inoperative position. Spacer 24 is moved to inoperative position, leaving a clear space above the sash 32 so as to permit its elevation during the next operation.

35 Screen 26 will of course have been removed, and the user now with one hand grasps the finger grips 45, and with the other the crank 77 at the bottom of the sash. The horizontal pivot pins 41 are retracted, and crank 77 swung through a half circle as shown by the arrows in Fig. 1. This elevates the sash bodily, and causes it to be mounted on vertical pivots 80 and 73 respectively. The crank 77 is locked in position by entering the detent into the opening 79, so that the sash is supported in its elevated position.

Now, the sash will swing on a vertical axis, and either its exterior or interior pane surface positioned to the inside of the room.

If it is desired to remove the sash entirely, the operation is the same except that the rack 73 is not entered into the socket 74 for the purpose of elevating the window. Retraction of the pivot pins 41 disengage the sash entirely from the frame in this instance so as to permit its complete removal.

What is claimed is:

1. In a window the combination, with a frame, of a sash, a horizontal pivotal connection between the sash and frame, a vertical pivotal connection between the sash and frame, means for selectively engaging either connection to the exclusion of the other, a gear box movably mounted in the frame and including a driving connection with the sash for swinging the sash, and means for adjusting the gear box to sash-engaging and sash-disengaged positions.

2. In a window the combination, with a frame, of a sash, a horizontal pivotal connection between the sash and frame, a vertical pivotal connection between the sash and frame, means for selectively engaging either connection to the exclusion of the other, a gear box pivotally connected to the frame and including a driving connection with the sash for swinging the sash, and

means for adjusting the gear box to sash-engaging and sash-disengaged positions.

3. In a window the combination, with a frame, of a sash, pivot pins movably mounted in the sash and normally engaged with the frame, means on the sash for retracting said pins simultaneously to disengage said connection of the sash and frame, a gear box movably mounted in the frame and including a driving connection with the sash for swinging the sash when the sash is pivotally engaged with the frame, and means for adjusting the gear box to sash-engaging and sash-disengaged positions.

4. In a window the combination, with a frame, of a sash, horizontal pivot pins movably mounted in the sash and normally engaged with the frame, means for retracting said pins to disengage the horizontal connection of the sash and frame, a gear box swingably mounted in the frame and including a driving connection with the sash for swinging the sash on its horizontal connection, means for adjusting the gear box to sash-engaging and sash-disengaged positions, a rack mounted vertically to reciprocate in the sash, a geared connection between the rack and sash adapted to bring the rack into engagement with the frame to elevate the sash, and a vertical pivot pin carried by the frame in axial alignment with the rack and adapted to engage in the sash when the sash is elevated, for pivoting of the sash upon said vertical pin and rack with the horizontal pivotal connection and the driving connection between the sash and frame is disengaged.

5. In a window the combination, with a frame,

of a sash pivotally mounted therein, a gear box pivotally mounted in the frame and including a driving connection with the sash for swinging the sash, and means for adjusting the gear box to sash-engaging and sash-disengaged positions, said means comprising a lock rod pivotally connected at one end to the gear box and mounted for slideable reciprocation in the frame, said lock rod when adjusted to one extreme position engaging the gear box with the sash and when adjusted to the other extreme position disengaging said gear box from the sash, and means for releasably securing the lock rod against movement from said extreme positions.
